(57) **CLAIM**

The ornamental design for a syringe component, as shown and described.

DESCRIPTION

FIG. 1 is an isometric view of a bottom, rear, and right side of an ornamental design for a syringe component;

FIG. 2 is an isometric view of a bottom, rear, and right side of the syringe component of FIG. 1 with environmental portions removed for clarity;

FIG. 3 is an isometric view of a top, front, and left side of the syringe component of FIG. 2;

FIG. 4 is a right side elevational view of the syringe component of FIG. 2, the left side elevational view being identical thereto;

FIG. 5 is a front elevational view of the syringe component of FIG. 2, the rear elevational view being identical thereto; FIG. 6 is a top plan view of the syringe component of FIG. 2; and,

FIG. 7 is a bottom plan view of the syringe component of FIG. 2.

The dash-dash-dash broken lines are included for the purpose of illustrating environmental structure and form no part of the claimed design.
